UNITED STATES PATENT OFFICE.

GEORGE KINGSTON, OF KOKOMO, INDIANA.

CARBURETER.

1,168,513.

Specification of Letters Patent. Patented Jan. 18, 1916.

Application filed January 5, 1912. Serial No. 669,631.

To all whom it may concern:

Be it known that I, GEORGE KINGSTON, a citizen of the United States of America, residing at Kokomo, in the county of Howard and State of Indiana, have invented certain new and useful Improvements in Carbureters, of which the following is a specification, reference being had therein to the accompanying drawings.

This invention relates to carbureters of the type in which the supply of gasoline is controlled by a float, and its object is to provide a construction which will insure the even supply and accurate regulation of the feed at all speeds of the motor, the invention consisting in the providing of a construction in which carbureted charges are supplied, during the normal running of the motor, to a manually controlled main air passage through an auxiliary air passage in which the fuel is atomized by the air passing therethrough and by the head of fuel maintained by the float, charges for running at low speeds being supplied by the auxiliary passage only.

The invention further consists in providing certain other new and useful features in the construction and arrangement of parts, all as hereinafter more fully set forth and particularly pointed out in the claims, reference being had to the accompanying drawings in which—

Figure 1 is a side elevation of a device embodying the invention with parts broken away to show the construction; Fig. 2 is a view of the same taken at right angles thereto, with parts broken away and in section; Fig. 3 is a horizontal section on the line x—x of Fig. 1; Fig. 4 is a sectional detail of one of the spray nozzles; Fig. 5 is a perspective view of a throttle valve detached; and Fig. 6 is a detail view showing a modified form of throttle valve in place.

As shown in the drawings, 1 is a body of the carbureter forming a float chamber 2 which is closed at its upper end by a cap or head 3 having an axial tubular portion 4 extending downward in the float chamber and opening through the bottom thereof, forming a central vertical air passage 5 through the carbureter to the upper end of

which the intake pipe or manifold of the engine may be secured. A float 6 in the float chamber is connected in any suitable manner, as by a lever 7, with a valve 30 to control the inlet of gasoline into the chamber and maintain a fuel level therein.

Preferably formed integral with the sides of the tubular member 4 within the float chamber, are two feed members 8 and 9 extending longitudinally of the tube downward into the float chamber to near the bottom thereof and each of these members is formed with two parallel bores. One of the bores in each member forms an auxiliary air inlet passage 11 opening through the top of the head 3 at its upper end, and the other bore in each member forms a feed passage 12 which communicates at its lower end with the lower end of the adjacent passage 11 through radial ducts 13 and an annular connecting duct 15 formed in the end of a screw plug or spray nozzle 14 screwed into the end of said passage, and through a duct 16 connecting said annular duct and the lower end of said passage 11. A small axial bore 17 in the plug 14 serves as a passage to admit gasoline from the float chamber into the passage 12 and this gasoline inlet is controlled by a needle valve 18, the stem 19 of which extends outward in said passage and is enlarged and screw-threaded at its outer end to close the outer or upper end of the passage and to provide an adjustment for the valve and its stem which may be turned by means of a head 20 on its outer end. A like arrangement of spray nozzle and needle valve is provided in each of the members 8 and 9, and outlet openings 21 and 22 for the passages 12 are provided intermediate the ends thereof above the normal level at which the gasoline is maintained in the float chamber by the float, these outlets opening directly into the main air passage 5 through opposite sides thereof to deliver thereto the air which is drawn through the passages 11 upon the suction stroke of the engine and passes through the ducts 13 around the gasoline inlet 17, atomizing the fuel as it enters the passages 12 and thoroughly carbureting the air before it enters the main air passage leading to the engine.

The main air passage 5 is controlled by a throttle valve 23 secured upon a transverse spindle 24 by screws 33 indicated in dotted lines in Fig. 1, inserted in openings 34 in the 5 valve member, said spindle being mounted in bearings in the sides of the tube 4 and actuated by means of a lever 25 on its outer end to turn the valve within the air passage. The valve body is ellipsoidal in form, and 10 its major axis is of greater length than the diameter of the air passage so that when turned upon its minor axis which coincides with the axis of the spindle, its ends will contact the wall of the tube and completely 15 close the passage. The valve body is preferably formed with facets, two of which, 26 and 27, are accurately formed to correspond to the surface of the tube which they contact when the valve is closed, and the valve 20 is so located relatively to the inlet openings 21 and 22 in the sides of the tube that the facet 27 will cover the opening 21 when the valve is closed and the facet 26 will contact the tube wall above the opening 22 to prevent 25 any vapor from being drawn therefrom by the suction stroke of the engine piston. A shallow notch 28 is cut in the facet 27 opposite the opening 21 so that said opening will not be quite closed by the closing of the 30 valve and the full force of the suction stroke of the engine piston will operate to draw charges through the opening 21 only.

When the valve is turned with its major axis in a vertical position, the main air passage 5 is restricted by said valve owing to its thickness intermediate its ends, leaving a crescent shaped air passage, in cross section of the tube 4, at each side of said valve, and owing to the tapering form of the valve, 40 this restriction gives a venturi effect to increase the suction in the tube opposite the inlet openings 21 and 22 in the sides thereof so that when the throttle valve is open, carbureted charges will be drawn into the main 45 air inlet from both auxiliary feed passages, and thoroughly mixed with the air rushing inward through said main air inlet.

When the carbureter is out of operation, the passages 11 and 12 in each feed member 50 8 and 9 will gradually fill with fuel up to the level maintained in the float chamber, which level is just below the lower edge of the opening 21. In starting the motor, the operator closes the main air passage 5 by 55 turning the throttle valve 23 to the position shown in full lines in Fig. 1. Upon the suction stroke of the motor piston, the vacuum created in the passage 5 above said valve, will draw the accumulated gasoline from 60 the passages of the feed member 8 through the opening 21 with considerable force, spraying it into said passage through the notch 28, and sufficient air will follow in through said passages to form an explosive

charge. A starting or priming charge is 65 thus provided and the drawing in of the full charge is insured by the closing of the throttle which closes all inlets to the engine cylinder except through the feed member. Sufficient carbureted air will continue to be 70 drawn through said feed member 8 to run the engine at low speed as long as the throttle is in closed position, and when the throttle is opened, the air rushing through the restricted main air passage at each side 75 of the throttle will draw in additional charges of carbureted air from the feed member 9.

In Fig. 6, a modified form of throttle is shown. In this construction the facet 31 80 which corresponds to the facet 26, is extended and formed concentric with the axis of rotation of the throttle for a short distance so that when said valve is turned to open the same, the facet 32 corresponding 85 to the facet 27, will be moved out of contact with the wall of the tube before the facet 31 disengages the same and thus the main air passage opposite the feed opening 21 is opened slightly in advance of the opening 90 of the passage opposite the opening 22. Additional air for running at medium speed may thus be supplied to the carbureted air which is being drawn through the opening 21. 95

By locating the atomizing nozzles below the level of gasoline in the float chamber and arranging the air ducts around the outlet of said nozzle to discharge into the jet of gasoline, the fuel is drawn in and thoroughly atomized before it enters the main air passage, in the normal operation of the device, and when the device is out of operation the feed members fill with fuel by gravity to provide a priming charge. During the operation of the carbureter, fuel is drawn from the float chamber near its bottom through said nozzles and thus the feed will not be affected by the tipping of the carbureter and the uneven operation of the float. By means of the needle valves, the feeding of the gasoline may be accurately regulated, the valve in the feed chamber 8 being adjusted for low speed and the valve in the member 9, for high speed. A wide 115 range of adjustment and an even feed is thus secured.

Having thus fully described my invention what I claim is:—

1. In a carbureter, the combination with 120 a casing having a main tubular air passage, and means for introducing fuel into the air passing through said passage, of a valve pivotally supported in said passage and having a thickened middle portion and tapered toward its edges to produce the effect of a venturi restriction in said passage. 125

2. In a carbureter, the combination of a

1. In a carbureter, the combination of a tubular main air passage, means for introducing fuel into said passage opening through the side thereof, and a pivotally supported valve member in said passage having an enlargement intermediate its ends adjacent to its pivot to give the effect of a venturi restriction in the passage and adapted to be turned across and close the passage.
2. In a carbureter, the combination of a member forming a main air passage, means for introducing fuel into said passage and a valve pivotally supported in said member upon an axis extending transversely of said passage, said valve being enlarged intermediate its ends and tapered toward each end, in section transversely of its pivotal axis, to give the effect of a venturi restriction.
3. In a carbureter, the combination of a member forming a main air passage, means for introducing fuel into said passage, and a valve member pivotally supported upon a transverse axis in said passage and having an elliptical outline with its major axis extending lengthwise of said passage and thickened intermediate its ends, said valve member being formed with facets to engage the wall of the air passage.
4. In a carbureter, the combination of a tubular main air passage, means for introducing fuel into said passage, and a valve member pivotally supported upon a transverse axis in said passage and having an elliptical outline with its major axis extending lengthwise of said passage and thickened intermediate its ends, said valve member being formed with facets to engage the wall of the air passage.
5. In a carbureter, the combination of a tubular member forming a main air passage, means for introducing fuel into said passage opening through opposite sides thereof, a valve pivotally supported in said air passage adjacent to said openings, said valve being oblong with rounded ends and a thickened middle portion and adapted to engage the wall of said passage between one of said openings and the discharge end of the passage and close said passage.
6. In a carbureter, the combination of a tubular member forming a main air passage, an auxiliary air passage opening through the wall of said member, means for carbureting air passing through said auxiliary passage, and a valve having an elliptical outline pivotally supported in said main air passage and adapted to be turned to engage the wall of said tubular member below the point at which said auxiliary passage opens into the same to close said main passage.
7. In a carbureter, the combination of a fuel chamber, a tubular member forming a main air passage, a feed member extending downward in the fuel chamber to near the bottom thereof and formed with longitudinal bores connected at the lower end of said member and having an inlet for fuel at its lower end, one of said bores being open to the atmosphere and the other being adapted to discharge into the said tubular member above the level of fuel in the chamber, and a needle valve for controlling the said fuel inlet.
8. In a carbureter, the combination of a fuel chamber, a tubular member forming a main air passage, a feed member formed with parallel bores one of which opens through the upper end of said member and the other into the main air passage near the upper end of said member, an atomizing nozzle in the lower end of said member provided with passages connecting the bores and with a fuel passage for admitting fuel to the lower end of said feed member from the fuel chamber, and a needle valve controlling said fuel passage and having a stem extending outward through one of the bores in said member.
9. In a carbureter, the combination of a fuel chamber, a tubular member having openings in its sides extending through the fuel chamber in the axis thereof and forming a main air passage, a feed member at each side of the tubular member extending downward into the fuel chamber to near the bottom thereof and each formed with an auxiliary air passage communicating with the main air passage through the openings in the sides of said tubular member, valve controlled means for admitting fuel into each of said auxiliary air passages from the fuel chamber, and a valve pivotally supported in said main air passage and adapted to be turned to close the passage below one of the openings in the sides of said tubular member and above the other of said openings.
10. In a carbureter, the combination of a member forming a main air passage having openings in opposite sides thereof, means for supplying fuel to said passage through said openings, and a valve pivotally supported in said passage having a portion at one side of its axis of rotation formed concentric with said axis to move adjacent to the wall of said passage over one of the openings when the valve is turned and hold said opening closed during a portion of the movement of the valve.
11. In a carbureter, the combination of a member forming a main air passage, means opening into said passage through opposite sides of said member for supplying fuel thereto, and a valve pivotally supported upon a transverse axis in said member and formed with facets to engage the wall of the passage adjacent to said means, one of said facets being extended and formed concentric with the axis of rotation of said valve.
12. In a carbureter, the combination of a tubular member forming a main air passage and having openings in its sides for admission of fuel to the passage, and a valve pivotally supported upon a transverse axis in said passage to be turned to engage the wall of said passage adjacent to said openings.

ing therein at one side of said valve and to engage said wall above the said opening at the opposite side of said valve, said valve being enlarged intermediate its ends and 5 tapered toward each end and formed with a face concentric with its axis of rotation at one side thereof.

In testimony whereof I affix my signature in presence of two witnesses.

GEORGE KINGSTON.
